UNITED STATES PATENT OFFICE.

EMIL BOMMER, OF NEW YORK, N. Y.

SPRING-HINGE.

1,131,664.

Specification of Letters Patent. Patented Mar. 16, 1915.

Application filed March 16, 1914, Serial No. 825,040. Renewed January 16, 1915. Serial No. 2,723.

To all whom it may concern:

Be it known that I, EMIL BOMMER, a citizen of the United States of America, and a resident of the borough of Brooklyn, county of Kings, city and State of New York, have invented certain new and useful Improvements in Spring-Hinges, of which the following is a specification.

This invention relates to spring-hinges and more particularly to improvements therein so as to provide special devices for the purpose of facilitating the lubricating of the operative parts on the one hand, and on the other hand, provide advantageous means for locking the parts in position.

The object of the invention is to provide means for this purpose and to do so at a reasonable cost of manufacture and simplicity in the assembling of the parts.

For this purpose my invention consists of the improved features hereinafter described and finally pointed out in the claims.

In the accompanying drawing, Figure 1 is a front view of a single-acting spring-hinge provided with my improved device, Fig. 2 is a corresponding section taken on line 2—2 of Fig. 1, Fig. 3 is a vertical section taken on line 3—3 of Fig. 2, Fig. 4 is a side view of a portion of the pintle having a lug thereon, Fig. 5 is a section of Fig. 4 taken on line 5—5, Fig. 6 is a perspective view of the leaf with an ear having the pintle opening provided with an additional recess to be engaged by the lug of the pintle, Fig. 7 is a perspective view of an improved form of washer used in the coöperation of the parts shown in the various figures.

Similar characters of reference indicate corresponding parts throughout the several figures of the drawing.

Referring to the drawing, and more particularly to Fig. 1, a form of well-known single-acting spring-hinge is shown therein, but my invention is not limited in its application to a single-acting spring-hinge. The leaf 10 is provided with the ears 11 and 11¹, and the leaf 12 is provided with the barrel 13. The leaves 10 and 12 are provided with the usual screw-holes 14 to enable the spring-hinge to be attached to the door and door casing by screws or the like. Interposed between the barrel 13 and the ears 11 and 11¹, are the usual spring-holders 15 and 15¹, and passing through perforations of the ears 11 and 11¹ of the leaf 10 and the spring-holders is a pintle 16 which is provided at

its ends with screw-threaded portions, one end being clearly shown in Figs. 3 and 4, the screw-threaded portion being indicated by 17. The screw-threaded portions 17 are provided with pintle heads or nuts 18 of any suitable shape. A coil spring 19 is interposed between the spring-holders 15 and 15¹. The parts in so far as have been just referred to are all well-known, and modifications may be made therein in the manner known to those skilled in the art.

To provide improved oiling means for the spring-hinge, the spring-holders 15 and 15¹ are provided with a depression or recess 20 and interposed between the ear 11 and spring-holder 15 is a washer 21, one form of this washer being shown clearly in Fig. 7, and this is provided with a central opening 22 to enable the pintle to pass therethrough, and with a radial slot 23. The ear 11 is provided with an opening 24 for the purpose of permitting the pintle to pass therethrough, the opening 24 of the ear 11 being provided with an extension recess 25. The pintle 16, which is clearly shown in Fig. 4, is provided near one of its ends with a lug 30, which is forced out of the material forming the pintle so as to have the configuration shown in Figs. 3 and 4, and clearly shown in cross-section in Fig. 5. By thus forming a portion of the material constituting the pintle 16 to form the extended lug 30, the portion of the pintle adjacent each side of the lug 30, is flattened, as clearly shown at 31 in Fig. 5, and also in Fig. 4. The length of the lug 30 is approximately equal to the combined thickness of the ear 11 and washer 21. The width of the lug 30 is determined approximately by the width of the recess 25 of the ear 11 and radial slot 23 of the washer 21.

When the parts are assembled, in the manner shown in Fig. 3, the pintle 16 has its lug 30 extending downwardly through the opening 24 and its extension 25 of the ear 11, and through the opening 22 and slot 23 of the washer 21, and preferably protrudes into the depression 20 of the spring-holder 15. The lug 30 is preferably loosely fitted into the recess 25 of the ear 11 and into the slot 23 of the washer 21, which gives a slight amount of play or freedom of movement to the correlated parts, whereby the lubrication is facilitated under the operation of the door. The oil is injected from an oil can or other device, into the radial slot 23 of the washer 21, and passes along the slot 23 to

the lug 30, and this lug aided by gravity and aided further by the slight independence of movement due to the more or less loose fitting of the parts, serves to guide and to 5 quicken the passage of the oil into the depression or recess 20, and to the other parts of the hinge. By the slight movement of the washer 21 in relation to the lug 30, and its semirotary to and fro movement upon the 10 spring-holder 15 when the door is operated, the oil is caused to spread between the washer 21 and the adjacent bearing surface of the spring-holder 15, while the lug 30 aids to distribute the oil along the pintle to 15 the other bearing surfaces of the hinge, so as to obtain the most efficient use thereof. The lug 30 of the pintle 16 gives the further advantage of locking the pintle in position in respect to the ear 11 and washer 21, whereby 20 the device heretofore proposed to accomplish this purpose, namely, providing the pintle with a hexagonal configuration of a washer having an opening commensurate therewith, as for instance shown in my co-pending application Serial No. 761,143 and also in my co-pending application Serial No. 825,089, both of which show a hexagonal configuration, is not needed, yet, nevertheless, the advantage of the united movement 25 of the pintle 16, ear 11, and washer 21 is obtained, and the permanent location of the slot on the periphery of the washer 21, in relation to the periphery of the ear 11 is established, and maintained for convenience in 30 lubrication.

My device is very simple in manufacture, and may be made without entailing any great cost, either in material or services, and at the same time lends simplicity to the assembling of the parts, and, lastly, insures a 35 very efficient means.

I have described an embodiment of my invention, but changes may be made therein without departing from the spirit of the 40 invention as defined in the appended claims.

I claim as new and desire to secure by Letters Patent:—

1. In a spring-hinge, the combination of a spring-holder provided with a depression, 50 a washer provided with a central perforation and a radial slot extending outwardly therefrom to the periphery of the washer, said slot communicating with the depression of the spring-holder, and a pintle having a lug, said lug extending into the radial slot of the washer.

2. In a spring-hinge, a spring-holder provided with a depression, a washer provided with a central perforation and a radial slot 55 extending outwardly therefrom to the periphery of the washer, a hinge-leaf provided with an ear having a central perfora-

tion and an additional recess extending outwardly therefrom, and a pintle passing through the ear, the washer, and the spring-holder, and having a lug engaging the additional recess of the ear and the slot of the washer. 65

3. In a spring-hinge, the combination of a pintle provided with a lug forced out 70 therefrom, forming an extension, a washer having a central perforation with a slot extending radially outward therefrom, the said slot having a slightly greater width than the width of the lug on the pintle, and 75 an ear provided with a central perforation and having a recess extending outward therefrom for engaging the lug on the pintle.

4. In a spring-hinge, the combination of 80 an ear provided with a central perforation and a recess extending outward therefrom, a washer provided with a central perforation and a slot extending outward therefrom, of a pintle for said central perforation of the ear and washer, said pintle having a lug for said recess and said slot, the recess of said ear being located to retain the slot of the washer and lug of the pintle in predetermined position for the convenient 90 injection of lubricating oil.

5. In a spring-hinge, the combination of a pintle having a lug forced out therefrom, a washer having a central perforation with a slot extending radially outward therefrom 95 and an ear provided with a central perforation having a recess extending outward therefrom, the lug of the pintle, slot of the washer, and recess of the ear being loosely fitted for quickening the movement of the 100 lubricant injected into the slot of the washer under the operation of the door.

6. In a spring-hinge having an ear and a washer, a pintle passing through the ear and washer, said pintle having a lug of a 105 length greater than the thickness of the ear or washer, in order to engage both ear and washer.

7. In a spring-hinge having an ear with a central opening and a recess extending 110 therefrom, and a washer having a central opening with a slot, a spring-holder having a depression, a pintle passing through the ear and washer and spring-holder, said pintle having a lug long enough to engage both 115 ear and washer, and enter a depression of the spring-holder.

In testimony, that I claim the foregoing as my invention, I have signed my name in presence of two subscribing witnesses.

EMIL BOMMER.
